UNITED STATES PATENT OFFICE.

WILLIAM T. SMITH, OF PHILADELPHIA, PENNSYLVANIA.

WOVEN PILE FABRIC.

SPECIFICATION forming part of Letters Patent No. 691,193, dated January 14, 1902.

Application filed October 28, 1901. Serial No. 80,233. (No model.)

To all whom it may concern:

Be it known that I, WILLIAM T. SMITH, a citizen of the United States, residing in Philadelphia, Pennsylvania, have invented certain 5 Improvements in Woven Pile Fabrics, of which the following is a specification.

My invention relates to that class of fabrics intended to simulate an oriental rug, these fabrics having a cut-pile face with elaborate 10 patterns both as to figure and coloring and having a plain back on which the figure is partially outlined by portions of the pile-threads drawn through to the back.

My invention consists of a fabric which 15 can be cheaply produced upon a loom, such as that employed for a "Smyrna" rug, the essential feature of the invention being the means employed to stiffen the chenille fur, which constitutes the patterned face of the 20 fabric, and to prevent said chenille fur from being drawn to the back of the fabric except to the limited extent desired.

In the accompanying drawings, Figure 1 is 25 an exaggerated section of a piece of fabric constructed in accordance with my invention, the section being taken in the direction of the warp; and Fig. 2 is a like exaggerated section of the fabric, taken in the direction of the weft.

30 The fabric comprises repetitions of two warp-threads 1 and 2 and three weft-threads 3, 4, and 5. The warp-threads 1 are separator warp-threads which extend throughout the fabric and serve to separate the face and back 35 weft-threads and also to determine the longitudinal stability of the fabric by preventing the same from stretching in the direction of the warp. The warp-threads 2 are binder warp-threads and serve to tie together the 40 face and back weft-threads of the fabric. The weft-threads 3 are composed of circular chenille fur, party-colored to produce the desired surface pattern of the fabric. The weft-threads 4 are heavy-spun threads, which 45 constitute the back of the fabric, and the weft-threads 5 are finer threads, which lie alongside the chenille-fur weft-threads 3 in

the same shed of binder-warp, and thereby impart stiffness to the bunch of threads constituting the core of the chenille, so as to 50 cause the fur or pile of the same to stand up well and rise after being depressed, thereby preventing the pile-surface of the fabric from showing foot-prints. The fine weft-threads 5 also serve to limit the extent to which the 55 chenille fur can be drawn down by the binding warp-threads 2 between the back weft-threads 4. Hence only a limited amount of the chenille pile or fur is visible on the back of the fabric, sufficient to faintly indicate the 60 outlines and coloring of the pattern, as in an ordinary expensive oriental rug.

In weaving the fabric a shed is first formed by raising the binding warp-threads 2 and lowering the separator warp-threads 1, and 65 into this shed is shot first the chenille-fur weft-thread 3, which is properly adjusted laterally to accord with the pattern on the preceding chenille weft-thread, after which the weft-shot 5 is inserted and beaten up. The 70 shed is then changed, the binding-threads 2 being lowered and the separator-threads 1 raised, and the back weft-thread 4 is then shot in and beaten up, these operations being repeated indefinitely. 75

Having thus described my invention, I claim and desire to secure by Letters Patent—

A woven fabric comprising face weft-threads of chenille fur, reinforcing face weft- 80 threads, each in a shed with one of the chenille weft-threads, heavy back weft-threads, separator warp-threads interposed between the face and back weft-threads, and binding warp-threads alternating with the separator 85 warp-threads and tying together the face and back weft-threads, substantially as specified.

In testimony whereof I have signed my name to this specification in the presence of two subscribing witnesses.

WILLIAM T. SMITH.
